UNITED STATES PATENT OFFICE.

OSWALD H. HANSEN, OF PORT WASHINGTON, WISCONSIN, ASSIGNOR, BY DIRECT AND MESNE ASSIGNMENTS, TO HANSEN CANNING MACHINERY CORPORATION, A CORPORATION OF WISCONSIN.

AUTOMATIC STOP MECHANISM.

Application filed January 8, 1921. Serial No. 435,835.

To all whom it may concern:

Be it known that OSWALD H. HANSEN, a citizen of the United States, residing at Port Washington, in the county of Ozaukee and 5 State of Wisconsin, has invented a certain new and useful Automatic Stop Mechanism, of which the following is a specification.

This invention relates in general to improvements in the art of controlling the operation of machines by means of objects delivered thereto, and relates more specifically to improved means for automatically stopping can filling machines and similar apparatus, under certain abnormal conditions of operation.

An object of the invention is to provide means for automatically controlling the operation of machines such as can filling machines, to which objects such as cans, are 20 delivered in succession. Another object of the invention is to provide simple and efficient means for stopping machines such as can filling machines, in response to certain abnormal conditions of operation thereof. 25 A further object of the invention is to provide means for positively eliminating waste of materials during the operation of automatic can filling machines.

In many canning factories, it is the established practice to transport empty cans or like receptacles to the filling machines with the aid of gravity, the cans being dropped or deposited in succession into the upper ends of can chutes leading from a can supply room to the filling machines located in a room below. As a rule, relatively cheap and unreliable help is depended upon to assort the empty cans and to keep the can chutes supplied so that the filling machines may be properly operated. The empty receptacles, and especially the relatively frail "sanitary" tin cans now almost universally used in the vegetable canning industry, are sometimes imperfect and for 35 this and other reasons, frequently become jammed in the can runways in spite of extremely careful handling and assortment of the cans. As a result of these and numerous other conditions, it often happens that 40 the delivery of empty receptacles to the filling machines is interrupted, thereby causing a machine to deliver batches of material which it was intended to deposit in the empty cans, upon the substructure of

the filling machine and over the floor of 55 the factory, thus wasting considerable material. As the attendants frequently fail to carefully observe the operation of the fillers, it often happens that a number of successive batches of material are thus 60 wasted before the normal supply of empty cans is reestablished.

The present invention contemplates the provision of means whereby such waste of materials is positively eliminated. With the 65 apparatus forming the subject of this invention, the machine to which the receptacles or cans are normally delivered in succession, is automatically stopped the instant the delivery of receptacles is interrupted. While 70 the invention has been illustrated for convenience, as being applied to a machine adapted to fill cans with a mixture of peas or beans and liquid, it will be obvious that the automatic stop device or mechanism is 75 also applicable to other types of can filling machines such as disclosed in Patents No. 1,188,764 and No. 1,359,367, and in copending applications Serial No. 197,809, filed October 22, 1917, Serial No. 214,205, filed 80 January 28, 1918, Serial No. 300,992, filed May 31, 1919, Serial No. 343,698, filed December 10, 1919, Serial No. 347,110, filed December 24, 1919, and Serial No. 430,131, filed December 13, 1920, as well as to other 85 machines which merely treat the cans or the contents thereof such as can washers and sterilizers.

Some of the novel features pertaining to the specific construction and operation of 90 can filling machines, form no part of the present invention and are claimed in copending applications Serial No. 197,809, filed October 22, 1917, Serial No. 214,205, filed January 28, 1918, and Serial No. 430, 95 131, filed December 13, 1920.

While the present specification makes use of relatively specific descriptive terms, it is not intended to thereby limit the scope of the invention. Although the machine illustrated is especially adapted to transport and to fill open topped "sanitary" tin cans in succession, the term "can" is intended to designate any type or form of receptacle. The term "filling" is not intended to designate a complete filling of the cans only, but is also intended to cover a partial filling of the receptacles as well.

A clear conception of an embodiment of the invention and of the operation of devices constructed in accordance therewith, may be had by referring to the drawings 5 accompanying and forming a part of this specification, in which like reference characters designate the same or similar parts in the various views.

Fig. 1 is a transverse vertical section 10 through a machine adapted to fill cans with a mixture of peas or beans and liquid, the machine having an automatic stop applied thereto.

Fig. 2 is a transverse vertical section 15 through a can feed mechanism for delivering empty cans in succession to a filling machine.

Fig. 3 is an enlarged part sectional view 20 of an automatic stop mechanism, showing the same applied to a filling machine.

Fig. 4 is an enlarged part sectional view 25 of the automatic stop mechanism, showing the same applied to a filling machine.

Fig. 5 is an enlarged part sectional view 30 of the automatic stop mechanism, showing the same applied to a filling machine.

Fig. 6 is an enlarged end view of the cam element for actuating the main power transmitting clutch of the filling machine.

The can filling machine disclosed in Fig. 1, to which the automatic stop mechanism is herein illustrated as applied, comprises in general a frame structure, a granular material supply hopper 2 mounted upon the frame structure, a liquid supply reservoir 3 supported by the frame structure, an annular series of seven equally spaced granular material measuring pockets 4 successively communicable with the supply hopper 2, an annular series of seven equally spaced mixture measuring pockets 5 successively communicable with the pockets 4 and with the supply reservoir 3, an annular series of seven equally spaced conducting elements 45 or funnels 6 successively communicable with the measuring pockets 5, means for transporting cans 30 in series below the successive funnels 6, and means for feeding or delivering successive cans 30 in succession 50 to the transporting means, the feeding mechanism being shown in detail in Fig. 2.

The frame structure comprises a pair of laterally spaced vertical side frames 20 which are interconnected at their lower portions by means of a horizontal cross-frame 24, at their medial portions by means of a horizontal can supporting frame 8, and at their upper portions by means of a horizontal pocket supporting frame 7. The 55 filler drive mechanism comprises a horizontal power shaft 16 supported in bearings formed integral with the frame 8 and in an outer bearing 35 secured to one of the side frames 20, and a vertical main shaft 10 60 supported in bearings in the several hori-

zontal frames and in the auxiliary frame 15. The shafts 10, 16 are drivingly connected by means of bevel gears 13, 14, the upper extremity of the vertical shaft 10 being positively connected to the pocket 70 forming elements so as to normally revolve the pockets 4, 5 about the shaft axis, and having a lower thrust collar 9 for preventing axial displacement of the shaft. The can transporting element 11 is attached directly to the bevel gear 13 by means of driving pins 23 and has a series of seven can hooks adapted to retain the successive cans 30 in vertical alinement with the lower openings of the funnels 6. The can guide 22 extends part way around the element 11 and is supported from the frame 8. The funnels 6 are also drivingly associated with the gear 13 and with the element 11 by means of the pins 23.

The main driving pulley 17 is secured by means of a key 40 to a clutch element 21 which is freely rotatable upon the horizontal power shaft 16 and which is held against axial displacement along this shaft by means of the bearing 35 and a collar 31 secured to the shaft 16, see Figs. 3 to 5 inclusive. The element 21 has a series of jaws 46 which with the clutch in driving position, are adapted to interlock with similar jaws on 95 the movable clutch element 18. The movable clutch element 18 is secured to the shaft 16 by means of a spline 45 and is manually movable into and out of engagement with the fixed clutch element 21 by means of a lever 19 which is adapted to shut off the supply of liquid to the reservoir 3 when the clutch is thrown out, and to establish a supply of liquid for this reservoir when the clutch is thrown in, as described in copending application Serial No. 430,131, filed December 13, 1920.

The can feeding mechanism shown in Fig. 2, comprises a curved can guide 25 the upper inlet end of which communicates with a supply chute not shown, and the lower delivery end of which terminates adjacent to the transporting element 11 and extends over a can feed drum 26. The guide 25 is adapted to right the successive cans 30 and to deliver them in succession upon the revolving upper surface of the drum 26. The end of the drum 26 adjacent to the shaft 10 is provided with a peripheral helical projection 27 which is adapted to engage the lower rear portions of the successive cans 30 and to whirl the cans successively upon the upper surface of the frame 8 and in advance of the approaching hooks of the transporting element 11. The feed drum 26 is secured to a horizontal counter shaft 28 mounted in bearings in the auxiliary frame 15, and is drivingly connected to the bevel gear 13 by means of a pinion 49. The filling machine is operable manually by means of a hand 120

wheel 29 secured to the shaft 28, while changing grades. The cans 30 after having been filled, are delivered from the machine by means of a discharge disk 50 located adjacent to the feeding mechanism. The can guide 22 extends from the feeding mechanism to the discharge disk and serves to hold the cans 30 in the path of the hooks of the transporting element 11.

10 The automatic stop mechanism shown in detail in Figs. 3 to 6 inclusive, comprises a rotary cam element 12 secured to the movable clutch element 18 by means of pins 48, a pair of united oscillatory arms 32, 33 secured 15 to the frame 8 by means of a pivot 37, an oscillatory actuating element 34 secured to the frame 8 by means of a pivot 38, and a tension spring 39 for constantly urging the actuating element 34 about its pivot 38 in 20 an anti-clockwise direction and toward a stop pin 43. The cam element 12 has a peripheral flange which is inclined at an angle of about 60 degrees relatively to the axis of the shaft 16. The greater portion of the 25 cam flange has circular generatrices whose common center is the shaft axis, but one portion 47 of the element flange is distorted toward the driving pulley 17 as shown in Figs. 4 and 5. The swinging end of the oscillatory arm 32 is provided with spaced rollers 36 which engage the opposite faces of the flange of the cam element 12. The swinging end of the oscillatory arm 33 is provided with a lug 41 which under certain conditions 30 of operation coacts with a similar lug 42 formed integral with the actuating element 34. The actuating element 34 is provided with a handle 44 for permitting manual oscillation of the element about its pivot 38.

40 During the normal operation of the filling machine, the clutch is thrown into driving position and rotary motion is being imparted from the pulley 17 to the shaft 16 and gears 14, 13. As the gear 13 is rotated, the shafts 10, 28 are simultaneously rotated, the former of these shafts revolving the pockets 4, 5 and the latter rotating the can feed drum 26. As the successive measuring pockets 4 pass the delivery opening of the supply hopper 2, they are filled with granular material from the hopper. The advancing filled pockets 4 subsequently and successively deliver their contents through an opening properly positioned, into the successive mixture measuring pockets 5. The advancing pockets 5 are subsequently and successively completely filled with liquid from the reservoir 3, thus producing successive homogeneous equal batches of mixture. These measured batches of mixture are subsequently and successively delivered from the pockets 5 through a properly positioned opening, into the successive funnels 6. As the can feed drum 26 rotates, the successive empty cans 30 are advanced from within the upper

portion of the guide 25 and are caught by the helical projection 27, see Fig. 2. The projection 27 whirls the successive cans 30 in advance of the successive can hooks of the revolving transporting element 11. The 70 hooks of the element 11 properly position and in conjunction with the guide 22, retain the cans 30 in vertical alinement with the discharge openings of the funnels 6 thus placing the empty cans in position to receive the measured batches of mixture passing through these funnels. As the successive cans 30 are filled with the mixture, they are delivered from the filler by means of the discharge disk 50. 75

During such normal operation of the filling machine with a proper supply of empty cans 30, the operation of the automatic stop mechanism is as follows, reference being had to Figs. 3 to 6 inclusive. As the cans 80 30 are initially advanced by the hooks of the element 11, they engage the stop actuating element 34 as indicated in Fig. 3. Upon being further advanced, the engaging can 30 swings the element 34 in a clockwise direction about its pivot 38 away from the stop pin 43 and stretching the spring 39 as shown in Fig. 4. When the element 34 is swung by a can 30, the lug 42 secured to the element is moved out of the path of travel 85 of the lug 41 on the arm 33, thereby releasing the arms 33, 32 for movement about their pivot 37. The timing of the rotary cam element 12 is such that during the period when the lugs 41, 42 are adjacent to each other, the rollers 36 of the arm 32 are in engagement with the undistorted portion 90 of the cam flange. When the lug 42 is moved away from the path of movement of the lug 41, the rollers 36 ride along the distorted portion 47 of the cam element 12 and momentarily swing the arms 32, 33 in a clockwise direction about the pivot 37 to the position shown in Fig. 4, without affecting the position of the clutch jaws 46. The rotating cam element 12 quickly restores the arms 32, 33 to the position indicated in Fig. 3 whereupon the can 30 releases the actuating element 34 and the spring 39 returns the released element to the position 95 indicated in Fig. 3 and against the stop pin 43. This sequence of operations of the levers 32, 33 and actuating element 34 occurs with the passage of each can 30 past the element 34. 100

If for any reason, the feed drum 26 fails to deliver a can 30 to the transporting element 11, the spring 39 retains the actuating element 34 against the stop pin 43 as shown in Fig. 5. With the element 34 and lug 42 105 thereon thus held, the arms 32, 33 are locked against clockwise movement by virtue of the coaction of the lug 41 with the lug 42. With the arm 32 thus locked, as the cam element 12 continues to rotate, the distorted cam 110

portion 47 automatically shifts the movable clutch element 18 to the right sufficiently to disengage the jaws 46 and to stop the filler. The shifting of the element 18 to the right as viewed in Fig. 5, simultaneously throws the clutch actuating lever 19 and shuts off the liquid supply to the reservoir 3. Upon restoration of the supply of empty cans 30, the filler may again be quickly placed in normal operation by manipulation of the lever 19.

From the foregoing description it will be apparent that the filling machine and the supply of material, will be quickly automatically stopped upon interruption for any cause of the can supply. The stop actuating element 34 is preferably so positioned that it will engage the relatively frail cans 30 at their bottom portions where they have greatest strength. The spring 39 is relatively light and will not damage the cans 30. The entire automatic stop mechanism is exceedingly simple and compact and may be readily applied to existing filling machines and to other kinds of can handling or treating apparatus.

It should be understood that it is not desired to limit this invention to the exact details of construction and of operation of the device herein shown and described, for obvious modifications within the scope of the claims may occur to persons skilled in the art.

It is claimed and desired to secure by Letters Patent:

1. In combination, means for advancing receptacles in series about an axis, a source of power, mechanism including a clutch for connecting said source and said advancing means, a member movable toward said axis and engageable with successive advancing receptacles of said series, and means operable by said member to disconnect said clutch when said series of receptacles is interrupted.

2. In combination, means for advancing receptacles in series about an axis, a rotary source of power having an axis of rotation transverse to the axis of advancement of said series, a clutch connecting said source and said advancing means, a cam for actuating said clutch, a pivoted member cooperable with successive receptacles of said series, and a connection between said member and said cam whereby said clutch is automatically disconnected when said series of receptacles is interrupted.

3. In combination, means for advancing receptacles in series about a vertical axis, a source of power comprising a pulley rotatable about a horizontal axis, a clutch rotatable about a horizontal axis and adapted to connect said pulley and said advancing means,

a vertically pivoted member movable in the path of and engageable with successive receptacles of said series, and a vertically pivoted arm operable by said member to disconnect said clutch from said pulley when said series of receptacles is interrupted.

4. In combination, means for advancing receptacles in series about a vertical axis, a driving pulley rotatable about a horizontal axis, a clutch having one element secured to said pulley and having another element drivingly connected to said advancing means, a pivoted member movable in the path of and engageable with successive receptacles of said series, a cam adapted to disengage said clutch elements, and means connecting said member and said cam to disconnect said clutch elements when said series of receptacles is interrupted.

5. In combination, means for advancing receptacles in series about an axis, means for delivering successive receptacles to said advancing means, a source of power, mechanism including a clutch for connecting said source and said advancing means, a member pivotally supported closely adjacent to said delivery means and movable toward said axis, said member being engageable with the successive receptacles entering said series, and means operable by said member to disconnect said clutch when said series is interrupted.

6. In combination, means for advancing receptacles in series about a vertical axis, means for delivering successive receptacles to said advancing means with their open ends uppermost, a source of power, mechanism including a clutch for connecting said source and said advancing means, a member vertically pivotally supported closely adjacent to said delivery means and movable toward said axis, said member being engageable with successive receptacles entering said series, and means operable by said member to disconnect said clutch when said series is interrupted.

7. In combination, means for advancing receptacles in series about an axis with their open ends uppermost, means for delivering successive receptacles to said advancing means, a source of power, mechanism including a clutch for connecting said source with said advancing and said delivery means, a member pivotally supported and movable toward said axis, said member being engageable with successive receptacles entering said series, and means operable by said member to disconnect said clutch when said series is interrupted.

In testimony whereof, the signature of the inventor is affixed hereto.

OSWALD H. HANSEN.
